UNITED STATES PATENT OFFICE

EMIL G. JURGENS AND HAZEN K. BECKER, OF CHICAGO, ILLINOIS, ASSIGNEES TO
PETERS MACHINERY CO., OF CHICAGO, ILLINOIS, A CORPORATION OF ILLINOIS

CARTON FORMING MACHINE

Application filed June 19, 1931. Serial No. 545,462.

This invention relates to the folding of blanks into carton form, together with lining paper therefor when desired, and it is of the same general class as the machine for setting up cartons and the like, disclosed in the patent of F. M. Peters, No. 1,025,880, dated May 7, 1912.

The purpose of the invention is to provide a simplified construction for reliably and rapidly performing the necessary folding of carton blanks which are successively fed to the machine, either by hand or automatically.

The invention may be carried into practice by means of a construction such as that illustrated in the drawings, in which:

Figure 1 shows the machine in front elevation.

Fig. 2 is a side view of the machine.

Fig. 3 is a plan view of the machine, but with the forming die omitted to show folding mechanism beneath, and it is partly in section as indicated by the line 3—3 of Fig. 1.

Fig. 4 is a large sectional view taken on the line 4—4 of Fig. 3.

Fig. 5 is a fragmentary sectional view taken on the line 5—5 of Fig. 1.

Fig. 6 is an enlarged fragmentary sectional view taken on the line 6—6 of Fig. 5.

Fig. 7 is an enlarged fragmentary sectional view taken on the line 7—7 of Fig. 3.

Fig. 8 is an enlarged sectional detail taken on the line 8—8 of Fig. 3.

Fig. 9 is a sectional view on the line 9—9 of Fig. 8.

Fig. 10 is a fragmentary sectional detail taken on the line 10—10 of Fig. 1.

Fig. 11 is a sectional plan view showing the motor drive for a machine taken on the line 11—11 of Fig. 1.

Fig. 12 is a sectional detail taken on the line 12—12 of Fig. 11.

Fig. 13 is a fragmentary detail to illustrate an automatic clutch as indicated by the line 13—13 of Fig. 1.

Fig. 14 is a plan view of the carton blank and lining paper thereon of the kind which is folded by means of this machine.

Figs. 15 to 19 are sectional views as indicated by the line 15—15 of Fig. 3, illustrating successive positions of the folding and end-flap-tucking element.

Fig. 20 is a perspective view of a folded carton ready for filling and as delivered by the machine.

Fig. 21 is a perspective view showing the carton lining paper partly folded and indicates, partly broken away, one of a pair of oscillating wings which aid in creasing the lining paper to prevent buckling of the paper at the back of the carton.

The purpose of this invention is to fold carton blanks, with or without lining paper, ready for receiving the contents to be packaged, such as lard, butter or vegetable shortening, which is flowed into the receptacle after delivery from the machine, the top of the carton being left open for this purpose.

Briefly stated the machine consists of a frame structure supporting a table top provided with a horizontally reciprocating blank receiving element which may carry the blank and lining paper placed thereon from a receiving position to a position under a vertically reciprocal forming element which moves downwardly, engaging the portion of the blank forming the bottom of the carton, and pressing it through a recess in the table, while the front, rear and side portions of the carton engage folding elements, most of which are movable in timed relation to effect the correct folding of the blank and the lining paper, and the interlocking of the end flaps.

Also operable in conjunction with these folding devices are plungers for opening slits in end members of the blank, in time for receiving an interlocking tongue, and a pair of oscillating lining paper creasing elements which assist in making a neat package in which the lining paper closely fits the walls of the carton.

Referring to the drawings, the frame structure 1 carries at its lower end, as illustrated in Figs. 1 and 11, a motor 2 for driving the machine through the reduction gearing 3. This gearing serves to drive the main drive shaft 4 through a clutch 5, under the control of the slidtable cone 6, which may be shifted to

start or stop the machine by manually operated lever 7.

During any continuous operation of the machine, the shaft 4 serves to continuously 5 reciprocate the carton forming die 8, Fig. 1, and a carton blank feeding element 22, Fig. 5, which serves to place the blank and also the lining paper beneath the die 8. The shaft 4 also intermittently drives the carton blank 10 folding devices shown in Figs. 15 to 19, inclusive.

The die 8 is secured to the underside of an arm 18, Figs. 1 and 2, extending horizontally from a pair of vertically reciprocal shafts 19, 15 guided in bearings in the machine frame and having a pitman connection 20 with a crank 21 on the shaft 4. Thus the die 8 is continuously reciprocated during the operation of the drive shaft 4.

20 The carton blank feeding mechanism, Fig. 5, includes a pair of adjustable elements 23, which engage the blanks edgewise during the horizontal motion of the member 22 toward the die 8. The edge of the lining paper 25 placed over the blank is engaged by the flange 24 carried by feed element 22. Fixed to the latter are racks 25 meshing with pinions 26 between these racks and stationary racks 27. The pinions are rolled along the racks 27 by 30 horizontal movement of their supporting shaft 28 under the action of an oscillating arm 29 pinned to a shaft 30, Figs. 1 and 2. The shaft 30 carries an arm 31, to which is pivoted a pitman 32, Fig. 12, operated by 35 cam 33 on shaft 4.

The carton folding mechanism is driven by a chain 34 connecting a sprocket 35 on shaft 4, with a sprocket 36, Fig. 8, carried by clutch element 37, freely rotatable upon 40 the drive shaft 38, for the blank folding mechanism. While the sprocket 36 is continuously driven, shaft 38 is intermittently driven in the same direction when clutched to the sprocket.

45 A clutch element 39 is splined to shaft 38, and rotated when a pin 40 supported thereon is turned so that a cut-away face 41 thereof is brought into position to be engaged by similar pins 42, carried by clutch element 37. 50 The pin 40 is rocked at the proper time for causing engagement of the clutch by means of a spring 43, Fig. 13, when a pawl 44 engages a finger 45 carried by pin 40.

This pawl is rocked to permit the clutch to 55 engage, and to be disengaged by the pawl again coming into the path of finger 45, by means of a pitman 46 operated by cam 47 on shaft 4. The finger 45 is limited in its movement by flat surfaces 48 thereof engaging the flat surface on clutch member 39.

The carton blank folding mechanism includes, as shown in Figs. 3, 4, 5 and 6, three shafts 50, 51 and 52. The shaft 38 drives the shaft 50 through the coupling 53. The 65 shaft 50 drives shaft 52 through the gearing

54, Fig. 7, and shaft 52, as shown in Fig. 6, carries a gear 55 for the purpose of driving shaft 51 through gear 56, Fig. 3. Shafts 50 and 51 carry folding elements 57, and the shaft 52 carries a pair of folding elements 58.

When a carton blank is deposited beneath the die 8 by the blank carrying mechanism 22, die 8 engages the blank at portion 59 thereof, Fig. 14, which forms the bottom of the carton. As the blank moves downwardly the front side 60 thereof is bent upwardly by the fixed shoulder 61, Fig. 5, of the table top. Simultaneously the end extensions 62 of the bottom 59 of the blank are bent upwardly by engaging the ends 63 of folding elements 58. The part of the blank forming the rear wall 64 and the top 65 of the carton, is bent upwardly by engagement with the top edge 66 of a wing 67, which at this time is in vertical position. Shafts 50, 51 and 51 rotate in the directions indicated by the arrows in Fig. 5, and after end portion 62 of the blank is bent upwardly by part 63 of the folding element 58, another portion 68 of this element engages the end portion 69 of the front side of the carton blank, and folds it rearwardly against the end portion 62.

After this occurs, as indicated by Fig. 16, the folding element 57, Fig. 17, folds the end element 70 of the blank forwardly. At this time the locking extension 71 of the carton end element 70 is slightly bent inwardly by stationary spring elements 72, as the die continues to travel downwardly. At this time, as indicated by Fig. 17, the end element 70 of the blank overlies the slotted part 69, with which it is finally interlocked. The interlocking takes place subsequently, as the purpose of the folding means so far described is merely to correctly fold the carton along scored lines.

The interlocking of the end flaps 69 and 70 is accomplished by returning the end and top portions 64 and 65 of the blank to the position indicated by Fig. 18, and again moving these portions of the blank forwardly so that the interlocking tongues 71 may enter the slots 73 while the tongues are guided inwardly and the slots held open by pressing members 74. To effect this interlocking of the carton ends, the wing 67 is oscillated. The shaft 75 supporting wing 67, as shown by Fig. 4, is provided with an arm 76 having a roller 77 for engaging cam 78, carried on a short shaft 79 with a gear 80, which meshes with one of the gears 54. The cam serves to rock the wing in one direction 125 against the action of the restoring spring 81, shown in Fig. 5. Rigid with the wing 67 are hook shaped members 82 which engage the end portions of the carton blank when the wing 67 rocks rearwardly and 130

compels the back portion of the carton to follow the wing, as indicated in Fig. 18.

After the interlocking has been effected, pins 83 on cams 58 engage the side edges of the folded carton as indicated in Fig. 19, and eject it downwardly from the machine. The folded cartons may be carried away by a traveling belt, not shown. The plungers or presser elements 74 which guide the locking tongues into the slots 73 are operated by cams 85 carried by shaft 52.

In case lining paper has been placed upon a blank as the latter is folded, the lining paper is folded with the blank in such manner that it may be withdrawn with its contents from the cardboard portion of the carton. The lining paper is folded around the die 8 with the cardboard blank, and in order to prevent the tendency of the lining paper to buckle along the rear wall of the carton, a pair of creasing wings 86, Fig. 1, are employed to correctly crease the lining paper along the back of the carton, as illustrated by Fig. 21, the crease referred to being indicated at 87. These wings are pivotally supported at 88 upon a fixed bridge 89 and are held separated by springs 90, Fig. 4. During the downward motion of die 8, a roller 91 carried by the die supporting arm 18 passes between the cam surfaces 92 of wings 86 and rocks the lower end of the wings toward each other. Roller 91 may be mounted as indicated in Fig. 10, so as to be ineffective on the up-motion of the die 8.

In operation of this carton folding machine, the continuously driven drive shaft 4 operates in correctly timed relation the horizontally reciprocating blank feeding mechanism illustrated in Fig. 5, the vertically reciprocating plunger or die element 8, and the rotating shafts 50, 51 and 52, which operate the folding device. These shafts are intermittently operated, the blanks being placed beneath the die between operations of the shafts.

When a blank is engaged by die 8 upon its downward motion, the part 59 of the blank forming the bottom of the carton, passes between the fixed edge 61, Fig. 5, the upper edge 66 of wing 67, and the extensions 63 of cams 58. Thus the forward and rearward walls and the end portion 62 are simultaneously folded upwardly, and then the end flaps 69 and 70 are successively folded against the end element 62 of the carton respectively by portions 68 of cams 58 and the cams 57. Then the wing 67 is rocked backwardly and forwardly to interlock the end portions 69 and 70 of the carton, while the locking tongues 71 are guided into the slots 73 by presser elements 74. The rear wall of the carton during the oscillation of wing 67 is preferably guided by stationary guide members 93.

The above described mechanism, while per-

forming the same folding operations, and somewhat the same ultimate result as with the other machines, for instance, the construction described in the previously mentioned patent to Peters, the manner of performing the operations, and the arrangement of the mechanism in the present case permit of an economical machine, capable of rapidly performing the desired actions, and insuring a highly satisfactory product.

Although but one specific embodiment of this invention has been herein shown and described, it will be understood that certain details of the construction shown may be altered or omitted without departing from the spirit of this invention as defined by the following claims.

We claim:

1. In a carton blank folding machine, a support for carton blanks having an opening therein, a reciprocating die for engaging a portion of the blank and forcing the blank through such opening, means for engaging side and end portions of the blank and folding them upwardly as the blank passes through said opening, a shaft extending parallel with one side of said opening and carrying end flap folding elements, means for rotating said shaft and the folding elements carried thereby, said folding elements being provided with means for engaging and ejecting the cartons after the folding thereof.

2. In a carton blank folding machine, a support for carton blanks having an opening therein, a reciprocating die for engaging a portion of the blank and forcing the blank through such opening, means for engaging side and end portions of the blank and folding them upwardly as the blank passes through said opening, a shaft extending parallel with one side of said opening and carrying end flap folding elements, means for rotating said shaft and the folding elements carried thereby, cooperating folding elements driven by said shaft and arranged to effect interlocking engagement between end portions of the folded carton.

3. In a carton blank folding machine, a table top having an opening therein, a blank feeding means movable horizontally along said table top for depositing carton blanks over said opening, a reciprocating die for pressing the blanks through said opening, rotary carton end folding and interlocking elements, and means for continuously driving said feeding means and die and intermittently operating said folding and interlocking elements.

4. In a carton blank folding machine, driving mechanism, means operated thereby for simultaneously folding a carton blank and lining paper therefor, and separate means for creasing the lining paper at the time the folding operation is performed.

5. In a carton blank folding machine, a

forming die, means for folding the side and end portions of the blank against the die, said means including rotary cams and a pivoted folding wing, means for producing two oscillations of said wing each time a blank is folded, and reciprocating plungers for guiding end tucking flaps on a blank as the wing oscillates.

6. In a carton blank folding machine, a forming die, means for reciprocating the die, a shaft at one side of the path of movement of said die and carrying folding cams for engaging end flap portions of the blank as the die moves by said shaft, a folding wing 15 at the opposite side of the path of movement of said die, end flap folding cams adjacent said wing, and means for intermittently ro-

tating said shaft and folding cams and oscillating said wing.

7. In a carton blank folding machine, a reciprocating die and cooperating folding elements, one of said folding elements being an oscillating wing having side hook-shaped extensions, means for producing two oscillations of said wing, one of the oscillations being for folding a carton and the other oscillation being for tucking the end flaps of a 75 carton, said side hook-shaped extensions being arranged to hook over the edge of the end tuck flaps of a carton and to draw them rearwardly before the completion of the tucking oscillation.
